CLAIM

The ornamental design for a pet food dispensing apparatus with storage tray, as shown and described.

DESCRIPTION

FIG. 1 is a perspective view of the top, front and right sides of a pet food dispensing apparatus with storage tray shown in a typical use configuration;

FIG. 2 is a front side elevation view of the pet food dispensing apparatus with storage tray;

FIG. 3 is a right side elevation view of the pet food dispensing apparatus with storage tray;

FIG. 4 is a rear side elevation view of the pet food dispensing apparatus with storage tray;

FIG. 5 is a left side elevation view of the pet food dispensing apparatus with storage tray;

FIG. 6 is a top plan view of the pet food dispensing apparatus with storage tray; and,

FIG. 7 is a bottom plan view of the pet food dispensing apparatus with storage tray.

The broken-lines in the above-described figures are for illustrative purposes only, and form no part of the claimed design.
